(57) CLAIM

The ornamental design for a blister pack pill tray, as shown and described.

DESCRIPTION

FIG. 1 is a frontal perspective view of a blister pack pill tray showing our new design;

FIG. 2 is a front view thereof;

FIG. 3 is a left side elevation view thereof;

FIG. 4 is a right side elevation view thereof;

FIG. 5 is a top view thereof;

FIG. 6 is a bottom view thereof; and,

FIG. 7 is a rear view thereof.
